CLAIM

The design for a combination gas pulsation dampener, cross and strainer, as shown and described.

DESCRIPTION

FIG. 1 is a perspective view of a first embodiment of a new and original design for a combination gas pulsation dampener, cross and strainer in accordance with the present disclosure;

FIG. 2 is a front elevation view of the combination gas pulsation dampener, cross and strainer shown in FIG. 1;

FIG. 3 is a rear elevation view of the combination gas pulsation dampener, cross and strainer shown in FIG. 1;

FIG. 4 is a right side elevation view of the combination gas pulsation dampener, cross and strainer shown in FIG. 1;

FIG. 5 is a left side elevation view of the combination gas pulsation dampener, cross and strainer shown in FIG. 1;

FIG. 6 is a top plan view of the combination gas pulsation dampener, cross and strainer shown in FIG. 1;

FIG. 7 is a bottom plan view of the combination gas pulsation dampener, cross and strainer shown in FIG. 1;

FIG. 8 is a perspective view of a second embodiment of a new and original design for a combination gas pulsation dampener, cross and strainer in accordance with the present disclosure;

FIG. 9 is a front elevation view of the combination gas pulsation dampener, cross and strainer shown in FIG. 8;

FIG. 10 is a rear elevation view of the combination gas pulsation dampener, cross and strainer shown in FIG. 8;

FIG. 11 is a right side elevation view of the combination gas pulsation dampener, cross and strainer shown in FIG. 8;

FIG. 12 is a left side elevation view of the combination gas pulsation dampener, cross and strainer shown in FIG. 8;

FIG. 13 is a top plan view of the combination gas pulsation dampener, cross and strainer shown in FIG. 8; and,

FIG. 14 is a bottom plan view of the combination gas pulsation dampener, cross and strainer shown in FIG. 8.

In the drawings, the broken lines depict unclaimed subject matter only and form no part of the claimed design.
